US0D1098638S

(12) **United States Design Patent** (10) **Patent No.:** **US D1,098,638 S**
(45) **Date of Patent:** **** Oct. 14, 2025**

(54) **PIPE CLEARING APPARATUS**

(71) Applicant: **Chongxia Xie**, Guangzhou (CN)

(72) Inventor: **Chongxia Xie**, Guangzhou (CN)

(**) Term: **15 Years**

(21) Appl. No.: **35/523,006**

(22) Filed: **Nov. 1, 2024**

(80) **Hague Agreement Data**

Int. Filing Date: **Nov. 1, 2024**

Int. Reg. No.: **DM/241899**

Int. Reg. Date: **Nov. 1, 2024**

Int. Reg. Pub. Date: **Nov. 22, 2024**

(51) **LOC (15) Cl.** **15-05**

(52) **U.S. Cl.**

USPC **D32/14**
